DESIGN FOR A WHEELED TOY

Nels H. Nelson, Minneapolis, Minn., assignor of
one-half to G. E. Norberg, St. Paul, Minn.

Application September 18, 1933, Serial No. 49,283

Term of patent 14 years

To all whom it may concern:

Be it known that I, NELS H. NELSON, a citizen of the United States, residing at Minneapolis, in the county of Hennepin and State of Minnesota, have invented a new, original, and ornamental Design for a Wheeled Toy, of which the following is a specification, reference being had to the accompanying drawing, forming part thereof,

Fig. 1 is a perspective view from the front and Fig. 2 a similar view from the rear of a wheeled toy, showing my new design.

I claim:

The ornamental design for a wheeled toy, as shown.

NELS H. NELSON.
